UNITED STATES PATENT OFFICE.

BENJAMIN N. HUESTIS, OF PHELPSTOWN, NEW YORK.

METHOD OF GENERATING ARTIFICIAL HEAT.

SPECIFICATION forming part of Letters Patent No. 234,190, dated November 9, 1880.

Application filed April 7, 1880. (No model.)

To all whom it may concern:

Be it known that I, BENJAMIN N. HUESTIS, of Phelpstown, in the county of Putnam and State of New York, have invented a new and 5 useful Improvement in the Art of Generating Heat, of which the following is a specification.

The invention relates to an improvement in the art of generating heat; and it consists in burning petroleum, either crude or refined, 10 over or in connection with a bed of calcium or of common lump-lime.

The invention is not limited in its application to any particular form of apparatus, it being only necessary that the usual boiler, 15 fire-box, and a blower be employed. It will be found essential to provide the blower with a cock, by which the supply of oil may be regulated, and generally to observe the steps which are customary in burning petroleum.

20 In operation, the boiler being filled with water, a sufficient quantity of broken lime is placed in the fire-box to cover its bottom, and enough oil then run in to saturate the same.

To ignite this I take a small piece of lime, 25 and, after wetting it with oil, light it with a match and apply it to the furnace. The blower is then turned on, the supply of oil being regulated according to the size of the furnace. The quantity of lime employed will depend

30 upon the size of the fire-box. It is desirable that enough be used to form a thick bed, al-

though a good result will be effected when even a small quantity is employed.

The nature of the invention having been explained, convenient and desirable methods of 35 practicing it will at once suggest themselves to persons skilled in the art to which it has relation.

As I conceive that I am the discoverer of the fact that calcium and petroleum may be 40 burned in conjunction with enhanced results, I do not limit my claim to quantities or proportions; but

What I do claim, and desire to secure by Letters Patent, is—

45 1. The process of generating heat, consisting in burning crude or refined petroleum in connection with calcium or with common lump-lime, as set forth.

2. The process of generating heat, consisting in burning petroleum in connection with a bed of calcium or of common lump-lime saturated with the oil, as specified.

In testimony that I claim the foregoing improvement in the art of generating artificial 55 heat, as above described, I have hereunto set my hand this 2d day of February, 1880.

BENJAMIN NEHEMIAH HUESTIS.
